DOOR MECHANISM

Application filed August 14, 1929. Serial No. 385,826.

This invention relates to improvements in door mechanism, and more particularly to improvements in mechanism associated with sliding doors of the type generally used in railway cars.

Various constructions have been proposed in which the door when in a position of rest seats upon a flat surface in order that the friction caused by the heavy weight of the door will prevent accidental and undesirable sliding movement of the door during shunting of the car, but when it is desired to move the door the construction is such that the door may be lifted and the weight transferred to supporting rollers, whereby an easy and frictionless movement of the door between open and closed positions may be had. It is desirable that the construction be such that the door will automatically drop to the flat seat when left unattended whether the door be in either open or closed position or at a point partially between the two.

It is an object of the present invention to provide a construction of door lifting mechanism whereby a very slight pressure is required upon the operating lever to raise the door and support it upon the rollers. In carrying out the first mentioned object of the invention, it is the purpose of the present improvements to provide mechanism which essentially consists of a double toggle arrangement whereby a high mechanical advantage is secured.

It is further an object of the present invention to provide, in connection with the door lifting mechanism, when associated with the lower edge of the door, door sealing means at the upper edge of the door whereby when the door is in lowered position it will be tightly sealed at both the upper and lower edges to prevent the ingress of the elements.

An additional object of the present improvements consists in a simple and practical construction such that the parts may be readily manufactured and assembled and replacement of parts may be readily had by providing a design such that the parts at the right and left-hand ends of the door are identical in form.

Further and additional objects and advan-

tages of the present improvements will be more readily apparent as the description proceeds, when taken in connection with the attached drawings, in which a preferred embodiment of the invention is illustrated.

55

In the drawings—

Figure 1 is a fragmentary front elevation of a freight car having the improved door lifting mechanism and door sealing means associated therewith, the door being illustrated in lowered position;

60

Figure 2 is a fragmentary view, similar to Figure 1, illustrating the lower portion of the door in elevated position;

65

Figure 3 is a fragmentary front elevation of the door lifting means and roller mechanism at one end of the door, the construction being shown on a slightly enlarged scale, the door being in lowered position;

70

Figure 4 is a view similar to Figure 3 but illustrating the door in raised position;

75

Figure 5 is a vertical section taken transverse to Figure 1, on the plane indicated by 5—5, the view being shown on a larger scale with portions broken away for clearness of illustration;

80

Figure 6 is a transverse vertical section, similar to Figure 5, but taken on the plane indicated by 6—6 in Figure 1;

85

Figure 7 is a vertical section similar to Figure 3, with a portion of the retaining housing broken away to more clearly illustrate the toggle links; and

90

Figure 8 is a fragmentary horizontal section taken on the plane indicated by 8—8 in Figure 1.

95

In the drawings, 10 indicates a freight car door of any ordinary type. 11 is a portion of a car side which includes a longitudinal Z-bar 12 at the top of the car and brackets 13—13 at the bottom of the car which support a track member 14. The track member 14 is substantially T-shaped in section and includes a top flange 15 and a vertical flange 16. The vertical flange 16 is riveted to the brackets 13 by the rivets 17.

100

The lower portion of the door 10 includes a sheet 18, which depends to extend behind the inner portion of the flange 15 and thus prevents outward swinging of the door. To

105

the sheet, as most clearly shown in Figure 6, is fastened, by the rivets 19, an angle member 20, the lower horizontal flange of which rests flatly upon the flange 15 of the track 5 when the door is in stationary position. The weight of the door is thus transmitted directly to the track through the flat engaging surfaces, and the friction is such that accidental sliding movement of the door is prevented.

The present construction also provides an improved design at the upper edge of the door, whereby when the door is in stationary position, the ingress of the elements within 15 the car is prevented by the cooperation of sealing means relatively carried by the car side and by the door. Thus, there is shown secured to the depending flange of the Z-bar 12 a deformed Z-bar 21 fastened by the rivets 20. The web 23 of the Z-bar 21 is in a horizontal position and extends over the top 25 of the door. From the web 23 depends a flange 24, which includes an inwardly bent edge 25 at the lower portion thereof.

Brackets or retainers 26 are fastened to the upper portion of the door by the rivets 27 and extend upwardly to overlap the vertical flange 24 of the deformed Z-bar 21. The 30 inner surface of the upper ends of the brackets 26—26 is arcuately shaped to contact with the flange 24 and prevent inward movement of the door. Also secured to the upper edge 35 of the door, by rivets 65, is an angle member 28 including an outwardly extending flange 29 overlapping the flange 25. Thus, when the door is in stationary position flatly seating upon the track 14, the flange 29 will contact with the flange 25 and thus seal the door.

Rollers 30 are associated with the lower 40 corners of the door and serve as rolling supports when the door is being moved. Similar to previous designs, means is provided for lifting the door to transfer the weight to the rollers during operative movements. It 45 will be apparent that present designs of steel doors call for a construction which has a considerable weight, and it is desirable that the raising means have a high leverage in order that the operator may raise the door 50 with as little work as possible.

The mechanism to be described is an improved construction which has a large mechanical advantage and is positive in its 55 action. The construction at both of the lower corners of the door is identical, and it will therefore be necessary to describe only one of the corner constructions.

There is provided a plate 31 which is fastened to the door sheet 18, and a U-shaped 60 housing member 32 having laterally extending legs 33 which engage the plate 31. The plate 31 and member 32 together constitute a housing and are fastened together to the door sheet 18 by the rivets 34. In coaxial 65 positions to the plate 31 and housing member

32 there are secured three pairs of pivot pins; thus there is a pair of lower pivot pins 35, a pair of left-hand pivot pins 36 somewhat above the pins 35, and a pair of pivot pins 37 to the right of the pins 35 and in line with the pins 36. A yoke-shaped operating member 38 includes depending arms 39 which extend past the sides of the roller 30 and have mounted therein the spindle 40, which provides a mounting for the roller 30. The yoke-shaped member 38 may therefore be termed a roller retaining member. Also outwardly extending from the lower portions of the arms 39 are three pairs of pivot pins which cooperate with the pins 35, 36 and 37, 70 already described. The construction is most clearly shown in Figure 7, in which there appears a lower pivot pin 41, a left-hand pin 42 somewhat above the pin 41 and a right-hand pin 43 in line with the pin 42. It will be understood that the corresponding pins on the opposite leg of the yoke member will be coaxially arranged. A toggle link 44 connects the pins 35 and 41, while a toggle link 45 connects the pins 36 and 42. Also, a 75 toggle link 46, similar to the link 45, connects the pins 37 and 43. It should be noticed that the pins 36 and 37 engage their respective links in slotted openings 47 and 48, while the remaining connections between the links and the pins comprise close fitting bearings. The pins extending from the housing include shoulders 64 to hold the links in place.

The upper end of the yoke member 38 is formed with a clevis 49, in the arms of which is mounted a transverse pivot pin 50, to which is connected an arm 51 including a cylindrical end 52 which is received in the end of a tubular cross connecting member 53. At the mid portion of the cross member 53 is fixed a 100 bracket 54, from which laterally extend bearing pins 55. The bearing pins 55 are received in the slotted openings 56 of a normally vertical lever member, generally designated 57. The lever 57 pivots about a pin 58, which is 105 mounted by the bracket 59 fastened to the door sheet 18 by the rivets 60. The lever also includes a cut out portion 61 in order to admit the cross member 53. The side portions 61^a, which are formed by the provision of the cut 110 out portion 61, are provided with the slotted openings 56, previously described. The upper portion of the lever 57 constitutes a handle 62 and is somewhat outwardly deflected from the door to permit an operator to readily grasp the handle. Suitable hasp securing means for the door of any ordinary type may be provided, as shown in Figure 1 and generally designated as 63.

In order to move the door from closed position, shown in Figure 1, the operator may either grasp the cross tubular member 53 and thrust it to the right if he is working from the ground level, or step upon the handle 62 of the lever 57 if he is working from a plat- 125

form. By either operation, a clockwise movement is imparted to each of the yoke members 38, which are normally in a substantially vertical position, similar to the lever 57. The 5 clockwise movement of each of the yoke members 38 will tend to move the axis of the roller pin 40 closer to the lower pins 35 which are fixed in position relative to the door. This 10 relative movement will impart an upward thrust to the door and move it to the position indicated in Figures 2, 4 and 5.

It will be apparent that during this movement the lower links 44 and the left-hand links 45 will act as toggles and thereby develop a 15 relatively high leverage, and the weight of the door will be divided between the pins 41 and 42 carried by the yoke members 38 and the pins 35 and 36 carried by the door. The 20 right-hand links 46 will merely serve as stop members to limit the upward movement of the door. A continuation of the thrust towards the right upon the cross connecting member 53 will result in movement of the door supported by the rollers 30. Upon release 25 of the pressure, the door will gravitally seat itself in its normal stationary position. The construction is such that the rollers when the door is in stationary position will only contact the track sufficient to prevent free 30 rotation of the rollers.

If the operator desires to move the door in the opposite direction there will merely be a reversal of the movements heretofore described. The door is prevented from inward 35 or outward swinging by the members already described, and the sealing means will efficiently operate to weather the door in the manner described.

Various modifications and changes may be 40 resorted to in the commercial embodiment of the present improvements without departing from the spirit of the invention as expressed in the appended claims.

What is claimed is—

45 1. In combination, a sliding door, a relatively fixed track, supporting rollers for said door adapted to travel on said track, housing members carried by said door, retaining members for said rollers received by said housing members, a plurality of connecting links between said housing members and said roller retainers, said links being pivotally connected to said roller retainers at points offset from the axis of said rollers, and means for turning said retaining members to lift said door.

50 2. In combination, a sliding door, a relatively fixed track, said door being mounted to gravitationally seat flatly upon said track when not in use, rollers for supporting said door for sliding movement, spindles for said rollers, mounting members for said spindles including integral lever arms, means for transmitting an operative movement to the ends of said lever arms, and means for communicating a lifting thrust to said door com-

55 prising links pivotally connected to said door and pivotally connected to said roller mountings at points offset from the axes of each of said rollers.

3. In combination, a sliding door, a relatively fixed track member, said door being mounted to gravitationally seat upon said track, supporting rollers designed to travel on said track and carry the weight of said door during sliding movement thereof, means for lifting said door to transfer the weight to said rollers, said means comprising a bar 60 horizontally mounted for movement parallel to said door, yoke-shaped roller retainers pivotally connected to the ends of said bar, housing members carried by said door and adapted to receive said yoke-shaped members and said rollers, and links connected to said yokes and said housing members whereby the movement of said bar will turn said yoke members and cause the door to be lifted.

4. In combination with a track, a door resting upon said track for frictionally resisting sliding movement along said track, a roller adapted to travel upon said track and carry the weight of the door when the door is moved, a lever on which the roller is rotatably mounted, said lever including upwardly and downwardly extending lever arms, a link member pivotally connected to the downwardly extending arm of said lever below the axis of said roller, said link being pivotally connected at its lower end to said door at a fixed pivotal point thereof, said link being in alignment with said lever when said door is frictionally resting upon said track, and operating means for said lever whereby the door may be raised relative to the axis of the roller to transfer the weight of the door to the roller as it travels upon the track.

5. In combination with a track, a door normally resting upon said track for frictionally resisting sliding movement along said track, a roller arranged to travel upon said track and receiving the weight of the door when the door is lifted relative to the track, a normally upright lever upon which the roller is rotatably mounted, said lever including upwardly and downwardly extending lever arms, a link member pivotally connected at its upper end to the downwardly extending arm of said lever below the axis of said roller and pivotally connected at its lower end to a fixed point on the door and operating means connected to the upwardly extending arm of said lever for turning said lever to raise the door relative to the axis of the roller.

6. In combination with a track, a door normally resting upon said track for frictionally resisting sliding movement along said track, a roller adapted to travel on said track and receive the weight of the door when the door is lifted relative to the track, a lever on which the roller is rotatably mounted, said

lever including a downwardly extending lever arm, a link member pivotally connected at its upper end to the downwardly extending arm of said lever member below the axis of said roller and pivotally connected at its lower end at a fixed pivotal point on the door, operating means connected to said lever for raising the door relative to the axis of said roller and a pair of slotted links between said lever and said door for governing the movement of said lever.

7. In combination with a track, a door normally resting upon said track for frictionally resisting sliding movement along said track, a roller arranged to travel upon said track and receive the weight of the door when the door is lifted relative to the track, a movable raising member rotatably supporting said roller, a link pivotally connected to a fixed point on said door and pivotally connected to said raising member at a point normally in alignment with the axis of said roller and the fixed pivot point on said door, a second link pivotally connected to said door at a point offset from the fixed pivot point of said first link and pivotally connected to said raising member at a point offset from the axis of said roller and means for operating said raising member to lift said door by lowering the axis of said roller relative to said door through turning movement of both of said links.

Signed at Chicago, Illinois, this 9 day of August, 1929.
